W. A. LEBUS

2,487,454

VACUUM BREAKER

Filed May 14, 1947.

Inventor:

William A. Lebus.

By: *Shee & Shee* Atty.

UNITED STATES PATENT OFFICE

2,487,454

VACUUM BREAKER

William A. Lebus, Chicago, Ill., assignor to The
Protectoseal Company, Chicago, Ill., a corpora-
tion of Illinois

Application May 14, 1947, Serial No. 748,036

4 Claims. (Cl. 220—44)

1

This invention relates to a vacuum breaker for containers of gasoline, or other highly volatile liquids, and its principal object is to provide a simple device for admitting air to the container whenever a partial vacuum is created therein by reason of the discharge of liquid from the container.

Another object is to provide a vacuum breaker of simple yet efficient form and which is not likely to get out of repair.

Other objects and advantages will appear in the course of this specification and with said objects and advantages in view this invention consists in the several novel features of construction, arrangement and combination of parts herein-after fully set forth and more particularly defined in the appended claims.

The invention is clearly illustrated in the drawing accompanying this specification in which:

Fig. 1 is a side elevation of a container equipped with a vacuum breaker embodying the simple form of the present invention;

Fig. 2 is a plan of certain members of the vacuum breaker; and

Fig. 3 is a central longitudinal section taken on the line 3—3 of Fig. 1.

Referring to said drawing the reference character 4 designates a container for containing gasoline, or other highly volatile liquids and it is here shown in the form of a cylindrical can having a dome-shaped top 5.

To the top 5 is welded, or otherwise secured an internally threaded bushing 6, into which is screwed the threaded end of a nozzle 7 which is usually provided with a valve actuating lever 8. A flame proof fire baffle 9 leads from the nozzle into the interior of the container.

Welded, or otherwise secured to the top 5 of the container is a neck 10, which encloses a filler opening 11 and as a preference the edge portion of the neck is bent down, as at 12, to provide a smooth edge for the neck. A flame proof fire baffle 33 extends down into the container from the neck. The flame proof fire baffles 9, 33, may be constructed in accordance with the disclosure in my prior Patent No. 2,351,526, dated June 13, 1944.

Welded, or otherwise secured to the neck 10 are ears 13, which are connected by a pin 14, and pivoted upon said pin 14 is a lever 15 which extends diametrically across the neck 10. The lever is formed with a handle 15a by means of which it is manipulated. Surrounding the pin 14 is a sleeve 16, and coiled about the sleeve 16 are two coils 17 of a coiled spring 18, the ends 19 of which

2

bear against the lever 15, the two coils are connected by members 20, which have a cross connection 21 that bears against the side of the neck 10. Preferably, the lever 15 is forked at its pivotal end, and the furcations 22 of the fork surround the pin 14.

A closure 23 is provided for closing the open end of the neck 10, and as shown said closure comprises a flanged cap 24 on the underside of which is held a pliable gasket 25 composed of treated leather, or other pliable material, which will not be injuriously affected by the contents of the container.

Secured to the cover 24 is a hollow post 26, formed at its lower end with a reduced hollow flaring neck 27, which is secured in a flaring opening 28 in the cover. The post extends into a socket member 29 formed in the lever 15 and is connected to said lever by a pin 30, here shown in the form of a cotter pin, which extends through the socket member of the lever and through the hollow post 26. There is sufficient clearance between the pin 30 and wall 31 of the bore 32 in the post, which receives the cotter pin, to allow air to flow into the hollow of the post whenever the hereinafter described valve is unseated.

Supported within the container, here shown as supported immediately below the closure 23 is a housing 34, which contains the valve mechanism of the vacuum breaker. Projecting up from the top wall 35 of the housing is a hollow screw threaded stud 36, which is threadedly secured in the post 26.

Formed upon the lower face of the top wall 35 is an annular rib 37 of tapered cross section, which acts as a seat for a disc valve 38, which is yieldably urged in an upward direction by a light coiled compression spring 39 to seat the disc valve upon the seat 37. As shown the disc valve comprises a pliable disc 40 and a flanged backing disc 41.

The lower open end of the housing is closed by a disc or disc-like wall 42 seated in a rabbet 43, formed in the vertical wall 44 of the housing. The metal at the lower end of the upright wall is peened over the edge of the disc 42, as shown at 45 to rigidly secure the disc 42 to the housing.

The disc 42 is centrally apertured as at 46 and is provided with an upstanding flared neck 47, around which the lower-most coil of the spring 39 is wound. The connection between the spring 39 and disc 42, just described, provides means whereby the spring is maintained in position on the disc, and the flange 41 on the backing disc 40 prevents the upper end of the spring from becoming

ing dislocated. The spring 39 is composed of very light gage spring wire, the tension of which is merely sufficient to hold the disc valve upon its seat.

The hollows in the post 26, the stud 36, the housing 34 and the disc 42 provide an air passage from the exterior of the vacuum breaker to the interior of the container.

In use the container is filled through the neck 10 by first raising the closure therefrom, after which the spring 18 is permitted to swing the lever 15 down and thereby seat the closure upon the upper edge of the neck.

When the liquid contents are poured out of the container a partial vacuum is created therein by the removal liquid and as a result the disc valve becomes unseated and air is permitted to enter the container through the air passages in the post, the threaded stud, the housing and the disc 42.

A handle 48 may be secured to the top 5 of the container whereby the container may be carried about and if desired trunnions, one of which is seen at 49, may be secured to a split ring 50 clamped upon the container and may form a pivotal connection between the container and a suitable stand 51, whereby the container may be tilted when pouring out the contents.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A container having a filler opening neck, a cover for closing the opening in the neck, a hollow post having its lower end secured to said cover, a lever pivotally mounted on the container and being formed with a socket to receive the post, a pin connecting the lever with the post, there being clearance between the pin and wall of the post for the admission of air to the interior of the post, means for yieldably holding the cover on the neck, a housing within the neck having a hollow screw threaded stud threadedly mounted in said post with the hollow of the stud providing communication between the hollow of the post and the interior of the housing, the latter having a top wall formed on its underface with an annular valve seat, a disc valve adapted to seat upon said seat, the lower end of said housing having an apertured wall secured thereto, and a light coiled compression spring secured on said apertured wall and bearing against said disc valve, whereby to yieldably seat said disc valve.

2. A container having a filler opening neck, a cover provided with a gasket for closing and sealing the opening in the neck, a hollow post having on its lower end a hollow neck secured in a hole in said cover, a lever pivotally mounted on the container and being formed with a socket to receive the post, a cotter pin connecting the lever with the post, there being clearance between the pin and wall of the post for the admission of air to the interior of the post, means for yieldably holding the cover on the neck, a housing within the neck having a hollow screw threaded stud threadedly mounted in said post with the hollow of the stud providing communication between the hollow of the post and the interior of the housing, the latter having a top wall formed on its underface with an annular valve seat, a disc valve adapted to seat upon said seat, the lower end of said housing having an apertured wall secured thereto, and a light coiled compression spring secured on said apertured wall and bearing against said disc valve, whereby to yieldably seat said disc valve.

underface with an annular valve seat, a disc valve having a disc of pliable material adapted to seat upon said seat, the lower end of said housing having an apertured wall secured thereto, and a light coiled compression spring secured on said apertured wall and bearing against said disc valve, whereby to yieldably seat said disc valve.

3. A container having a filler opening neck, a cover provided with a gasket for closing and sealing the opening in the neck, a hollow post having on its lower end a hollow neck secured in a hole in said cover, a lever pivotally mounted on the container and being formed with a socket to receive the post, a cotter pin connecting the lever with the post, there being clearance between the pin and wall of the post for the admission of air to the interior of the post, means for yieldably holding the cover on the neck, a housing within the neck having a hollow screw threaded stud threadedly mounted in said post with the hollow of the stud providing communication between the hollow of the post and the interior of the housing, the latter having a top wall formed on its underface with an annular rib of tapering cross section providing an annular valve seat, a disc valve having a disc of pliable material adapted to seat upon said seat, the lower end of said housing having an apertured wall secured thereto, and a light coiled compression spring secured on said apertured wall and bearing against said disc valve, whereby to yieldably seat said disc valve.

4. A container having a filler opening neck, a cover provided with a gasket for closing and sealing the opening in the neck, a hollow post having on its lower end a hollow neck secured in a hole in said cover, a lever pivotally mounted on the container and being formed with a socket to receive the post, a cotter pin connecting the lever with the post, there being clearance between the pin and wall of the post for the admission of air to the interior of the post, means for yieldably holding the cover on the neck, a housing within the neck having a hollow screw threaded stud threadedly mounted in said post with the hollow of the stud providing communication between the hollow of the post and the interior of the housing, the latter having a top wall formed on its underface with an annular valve seat, a disc valve having a disc of pliable material adapted to seat upon said seat, and a flanged backing disc carrying said pliable disc, the lower end of said housing having an apertured wall secured thereto, and a light coiled compression spring secured on said apertured wall and bearing against the flanged backing disc of said disc valve, whereby to yieldably seat said disc valve.
